UNITED STATES PATENT OFFICE.

ROBERT E. ANDERSON, OF LANCASTER, PENNSYLVANIA.

MATRIX HOLDER.

Application filed October 24, 1924. Serial No. 745,636.

To all whom it may concern:

Be it known that I, ROBERT E. ANDERSON, a citizen of the United States, and a resident of Lancaster, in the county of Lancaster and State of Pennsylvania, have invented certain new and useful Improvements in Matrix Holders, of which the following is a specification.

My present invention relates generally to matrix holders or hand devices in which to hold matrices, useful to operatives in the linotype, linograph and intertype printing industries, my primary object being the provision of a simple inexpensive device which may be formed from a single piece of sheet metal and cut and stamped to form in an operation involving minimum time, expense and effort.

A further object is the provision of a reversible matrix holder which may be quickly picked up and is then instantly in an operative position.

With the above in mind my invention resides in a matrix holder to be now described with respect to the accompanying drawing which illustrates my invention and forms a part of this specification and wherein—

Figure 1 is a perspective view of my improved matrix holder complete.

Figure 2 is a vertical transverse section taken therethrough, and

Figure 3 is a top plan view thereof.

Referring now to these figures and particularly to Figures 1 and 2 it will be noted that my invention proposes a matrix holder in the nature of an elongated open frame-like structure which is Z-shaped in cross section and which includes an intermediate or body portion 10 having angularly and oppositely bent side strips 11 and 12 along its opposite sides whereby either surface of the body 10 forms a matrix support in conjunction with one of the side strips 11 and 12, each of which constitutes a backing for one of the holding surfaces of the body.

The body is also provided at its opposite ends with triangular end pieces 13 as most plainly seen in Figure 1, and these end pieces bent at right angles to the body 10 and in opposite directions with respect

thereto, may be joined along their shorter sides with the adjacent ends of the side strips 11 and 12, as by means of soldering, brazing and the like so that each of the matrix holding spaces will thus have one end wall, and each of the side strips will be materially and sufficiently braced to avoid accidental bending thereof in use.

While it is not essential, it is preferable that the outer faces of the side strips 11 and 12 be graduated therealong as indicated at 14 in order that the operator may in this manner readily gauge the combined widths or thicknesses of a number of matrices indicated at A in Figures 1 and 2, resting in the holder.

It is thus obvious that either side of my improved matrix holder may be used and that when picked up by the operator it is instantly in position for use so that time and trouble is in this way avoided. It is also obvious that my invention not only fails to complicate the construction in securing the foregoing advantage but the holder provided by my invention is simple, inexpensive and durable.

I claim:

1. A reversible matrix holder consisting of an elongated member Z-shaped in cross section, including a body portion and angularly and oppositely bent side strips along the sides of said body portion.

2. A reversible matrix holder consisting of an elongated member Z-shaped in cross section, including a body portion and angularly and oppositely bent side strips along the sides of said body portion, and said side strips being graduated continuously along the outer faces thereof for the purpose described.

3. A reversible matrix holder consisting of an elongated member Z-shaped in cross section, including a body portion and angularly and oppositely bent side strips along the sides of said body portion, and triangular end pieces projecting angularly from the ends of the body, and each in bracing connection along one edge with the adjacent end of one of the side strips.

ROBERT E. ANDERSON.
